UNITED STATES PATENT OFFICE.

EUGÈNE SCHNEIDER, OF LE CREUZOT, FRANCE.

APPARATUS FOR ANCHORING GUN-CARRIAGES.

1,183,242.

Specification of Letters Patent. Patented May 16, 1916.

Application filed December 28, 1915. Serial No. 69,099.

To all whom it may concern:

Be it known that I, EUGENE SCHNEIDER, a citizen of the Republic of France, residing at Le Creuzot, France, have invented a new and useful Improvement in or Relating to 5 Apparatus for Anchoring Gun-Carriages, which is fully set forth in the following specification.

This invention has for its object to provide 10 an improved apparatus for anchoring gun carriages which are adapted to swing on a fixed vertical pivot mounted on the tail of the gun carriage trail.

The invention consists in an apparatus 15 that will allow of applying to this type of gun carriage a sliding spade, that is to say, a spade capable of variable depth of penetration into the ground, which remains independent of the gun trail in the direction 20 of its penetration, but will operate as one piece with the trail in such a manner as to absorb the shocks or strains of the recoil and of the running out again of the gun into the firing position.

25 The invention consists essentially in making the trail pivot in the form of a box or part of a box adapted to bear with a suitable base on the ground, and which comprises a guide in which a sliding spade can move up and down and be held in any desired position. The tail of the trail is formed with an eye in which the said pivot is mounted. In other words, the usual pivot of a gun carriage adapted to swing 30 on its trail spade is, according to the present invention, so constructed as to serve as a guide for the sliding movement of a spade capable of variable depth of penetration 35 into the ground. Sliding spades have already been employed in a slide in the trail tail.

The invention also consists in a locking device which allows of locking the pivot relatively to the trail if desired, either during transport or during the driving of the 45 sliding spade into the ground.

Two embodiments of this invention are illustrated by way of example in the accompanying drawings.

50 Figures 1-5 show one embodiment. Fig. 1 is a partial sectional elevation of a gun carriage adapted to swing on a vertical pivot carried by the trail and provided with the improved anchoring apparatus. The head 55 of the mounting slides in the usual manner

on a guide carried by the axle. Fig. 2 is a plan corresponding thereto. Fig. 3 is a detailed section drawn to a larger scale of the gun trail tail and of the anchoring apparatus. Fig. 4 is a corresponding plan. Fig. 60 5 is a section similar to that of Fig. 3 showing the carriage pivot in a different position. Figs. 6, 7 and 8 illustrate the other embodiment of the invention. Fig. 6 is a detail section of the tail of the carriage and 65 of the anchoring apparatus on the line VI-VI of Fig. 7. Fig. 7 is a plan in partial section corresponding thereto. Fig. 8 is a front elevation of the anchoring apparatus shown separate from the gun carriage. 70

In the embodiment shown in Figs. 1 to 5, A is the gun trail adapted to slide in a known manner with its head along a guide B formed on the axle C. According to this 75 invention the pivot of the trail tail a is constituted by a cylindrical box D-D, the bottom of which is slightly splayed by means of a foot d. The box forms by means of transverse partitions d¹, d¹, provided between the top and the bottom of the box, and by means of the partial vertical walls d², d³, formed in one piece with said top and bottom, a slide for an independent spade E which is thus guided exactly in the pivot. 80 The tail a is formed with an eye or collar a¹, by means of which it fits exactly on the wall d², d³ of the box, in such a manner as to be capable of swinging around the latter. In all positions of the gun carriage the 85 spade acts thus like the trail spade of the Deport system, that is to say, it remains independent of the gun carriage in the direction of its penetration in the ground, while it becomes as it were one piece with the gun 90 carriage, by means of the pivot D-d¹-d¹-D and the collar a¹, for the purpose of taking the strains due to the firing of the gun. The pivot box may be provided at its upper 95 part with a stop such as a spring-pressed bolt F, provided with teeth coöperating with teeth e formed on the independent spade E and intended to prevent an untimely rising of the embedded spade. In the wall of the collar a¹ there may be mounted 100 a turning bolt G of known construction, for which two diametrically opposite sockets d⁴ are provided on the lower edge of the partial wall d² of the pivot box. The operating 105 crank handle g of the bolt is adapted to engage 110

gage the end g^1 of its spring stud in catches h provided in projections H^1 of the casing H of the bolt G .

By means of the apparatus just described, 5 by rotating the pivot box $D-D$ in the collar a^1 of the trail, before depressing the trail, the spade can be brought into the position shown in Fig. 5, wherein it has an inclination the reverse of that which it has in the 10 positions shown in Figs. 1 to 4. This position is suitable for firing rapidly a first shot from the gun in the case of surprise.

Figs. 6, 7 and 8 illustrate the other embodiment in which the pivot box is composed of two plates D, D in a central hole of which there is engaged the pivot proper D^1 . Guides d^1-d^1 are formed on each side of the axis of the pivot for two sliding spades E, E . The trail tail a contains a 20 socket a^1 through which the pivot D^1 passes when the box is in position on the trail. $G-g$ is a stop similar to that described in the preceding example. According to the 25 position which is given to the pivot box relatively to the gun trail, the said stop allows of fixing the pivot box for the purpose of driving in the spades in the direction shown, or in the symmetrically reverse direction. Namely, if it is desired to reverse 30 the direction of the spades, it is merely necessary to remove the pivot D^1 by withdrawing the pin I , then to disengage the box and replace it in the required position by 35 turning it around, so that the guides will thus have given to them a direction which is the reverse of the direction they had previously.

What I claim is:—

1. In apparatus for anchoring a gun carriage of the type wherein the gun mounting is adapted to swing around on a trail spade as on an axis, the arrangement that the pivot of the gun carriage is constituted by, or is carried by a box-like part comprising 40

Copies of this patent may be obtained for five cents each, by addressing the "Commissioner of Patents

Washington, D. C."

one or more accurate guides for one or more 45 sliding spades, a device being provided for locking said box-like part to the trail for transport purposes or for the penetration of the sliding spade or spades in two symmetrical positions of inclination.

2. In apparatus for anchoring a gun carriage of the type specified, the combination with the gun carriage trail and a trail spade around which the gun mounting is adapted to swing as on a pivot, of an approximately vertical hollow cylindrical bearing in said trail, an externally cylindrical box-like support mounted in said bearing, and a guide slide inclined to the vertical in said bearing adapted to receive 60 and guide the spade in its upward and downward sliding movements.

3. In apparatus for anchoring a gun carriage of the type specified, the combination with the gun carriage trail and a trail spade 65 around which the gun mounting is adapted to swing as on a pivot, of an approximately vertical hollow cylindrical bearing in said trail, an externally cylindrical box-like support mounted in said bearing, a guide slide 70 inclined to the vertical in said bearing adapted to receive and guide the spade in its upward and downward sliding movements, whereby by revolving said box-like support in its bearing, the spade can be 75 revolved about an approximately vertical axis independently of the trail, and means for locking said support at any point of its revolution to said bearing, whereby the spade can be locked at any desired point 80 relatively to the trail.

In testimony whereof I have signed this specification in the presence of two subscribing witnesses.

EUGÈNE SCHNEIDER.
